PROCESS FOR CONVERTING HIGH BOILING POINT OILS

Robert E. Wilson, Chicago, Ill., assignor to Standard Oil Company, Whiting, Ind., a corporation of Indiana

Application November 1, 1926, Serial No. 145,515
Renewed January 8, 1932

10 Claims. (Cl. 196—47)

The present invention relates to improvements in processes for effecting the conversion of higher boiling point distillate oils, such as naphtha bottoms, gas oil and heavier distillates, if desired, into lower boiling point hydrocarbon oils, for example, of the gasoline range of boiling points. It will be fully understood from the following description, illustrated by the accompanying drawing, in which apparatus capable of carrying out the present invention is shown diagrammatically in section.

The drawing shows a sectional view through a furnace and illustrates diagrammatically the arrangement of the tubes through which the oil to be converted is forced in carrying out a process exemplifying the present invention. In the lower portion of the furnace setting 5 there is provided one or more combustion chambers 6, to which fuel is supplied by burners 7 and in which combustion takes place. The walls 8 of the combustion chamber are constructed of a suitable refractory material capable of withstanding the direct heat of the flame; for example, they may be constructed of carborundum or other similar material. Combustion takes place substantially completely within the combustion chambers 6 and the combustion gases pass therefrom into a large flue 9 in the rear of the furnace by which they are conducted to the upper portion of the furnace as hereinafter set forth. A vertical wall or partition 10 separates a compartment above the combustion chamber 6 from the flue 9 which receives the combustion gases, and this compartment, indicated by the numeral 11, is closed at its top by the partition 12 of fire brick or other suitable refractory material, such as a suitable chromium-iron alloy. The compartment 11 is exposed to the radiant surface of the walls 8 of the combustion chambers 6 and is heated substantially entirely by radiant heat therefrom, although if desired, it may be in part heated by combustion gases. The portion of the setting above the compartment 11 may be divided into two passes, as by partial partition 13 of suitable refractory material. Of these the lower pass is indicated by the numeral 14 and the upper pass by the numeral 15. The combustion gases from the combustion chamber 6, pass upwardly through the vertical flue 9 and then traverse successively the flues 14 and 15, finally reaching the stack 16.

The tubes which receive the oil to be converted are mounted within the furnace and are designated individually by the numeral 17. These tubes are connected in series in sections and the pass of the oil therethrough is as follows:

The oil enters the furnace through the inlet pipe 18 and first traverses the economizer section in the pass 15 nearest the stack travelling in countercurrent to the flow of combustion gases.

This section extends from broken line A to broken line B in the form shown in the drawing. From this section the oil passes through line 19 (suitably a thermally insulated line passing outside of the furnace) to the screen section of pipes in the pass 14 first reached by the combustion gases. This pass extends from C to D and through this pass the oil flows concurrently with the flow of the combustion gases. From the last pipe of this section, at the point D, the oil flows through the line 20 to the lower of the rows of pipes located in the compartment 11, heated by radiant heat from the walls of the combustion chamber 6. The oil then travels in series through the pipes of this radiant section, first traversing the row of pipes nearest the combustion chamber and then in succession the more remote rows of pipes in the compartment 11, finally making its exit from the last pipe of the uppermost row through the line 21, by which it is conveyed to the first pipe of the soaking section extending from the point D in pass 14 to the point B in pass 15 traversed by the combustion gases. Through this section of pipes the oil flows concurrently with the flow of combustion gases.

From the above description of the flow of oil, it will be seen that it is first heated by the coolest combustion gases; it is then subjected to the action of the most highly heated combustion gases apart from any radiant heat action; it is then subjected to the heating action of radiant heat alone and finally again subjected to the heating action of the combustion gases. While the furnace is a preferred type of furnace for carrying out the present invention and the flow of the oil relative to the heating elements as hereinbefore set forth has likewise been found highly desirable, the invention is not limited either to the structure or the particular method of operation shown, as will be more fully hereinafter pointed out. The particular means herein set forth has the advantage that it is readily adaptable to the control of operation which constitutes the present invention.

In operating conversion processes under pressure, it has hitherto been found that the extent of conversion taking place in the coils must be carefully limited to 5, 10 or at most 12 to 13% as a maximum in order to prevent rapid choking of the coils by coking and consequent shut-down of the plant. I have found, however, that by operating in accordance with the present invention, more than 12% or even as high as 25% of gasoline boiling point hydrocarbons may be produced from higher boiling point hydrocarbons (of a distillate character) without excessive coking or choking of the coil and that even with heavy oils which form excessive amounts of coke in cracking, the proportion of gasoline which may be produced in a single operation may be very substantially increased.

In operating in accordance with the present invention I have found that it is necessary to correlate in a definite way the pressure of the operation, the maximum temperature attained and 5 the rate of transfer of heat to the oil at the various stages of its heating. Thus it is required to maintain a pressure upon the oil passing through the coils which, at the temperature prevailing therein at least under critical temperatures, will 10 permit the formation of vapor but will maintain the mixture of vapor and unvaporized liquid in the form of a foam in which the vaporized portion is maintained as discontinuous bubbles and yet not permit vaporization to the extent that the 15 unvaporized stock is carried along as drops or a film in a vapor medium. For example, with a charging stock passing through the coil of the nature of gas oil, and with a maximum temperature attained of about 915° F., a minimum pressure 20 of 1100 lbs. per square inch must be maintained. With variations in the maximum temperature attained, there may be corresponding variations in the pressure required; thus, as an approximate rule, it may be stated that a variation 25 of 15° F. in temperature attained in either direction requires a corresponding variation in the minimum pressure required of about 100 lbs. on the oil. Similarly, variations in the charging stock necessitate variations in the corresponding 30 temperature and pressure conditions. Thus, with a charging stock of the nature of naphtha bottoms, a minimum pressure of 1100 lbs. per square inch is required where the maximum temperature attained by the oil is about 880° F. With this as a 35 guide the required temperature pressure correlation may readily be determined for each charging stock by a short period of observation.

In conjunction with the required pressure and temperature conditions as hereinbefore set forth, 40 in accordance with my invention there should be a minimum velocity of the oil flowing through the tubes of at least 60 lbs., and preferably of about 80 to 90 lbs. of oil per square inch of tube cross section per minute; and with this, the heat must be 45 so applied that the metal wall of the tubes (while clean) through which the oil flows is at no point more than 20° F., and preferably not more than 10° F. above the maximum temperature to which the stream of oil is heated. By operating in this 50 manner, the most rapid application of heat occurs while the oil is at a temperature below about 750° F., and the rate of application of heat decreases as the temperature of the oil increases. Thus, in the type of furnace shown, after the oil leaves 55 the preheating section extending from A to B, it enters the highly heated section in pass 14 extending from C to D. The oil is still relatively cool at this time, being substantially below 750° F. and heat is therefore imparted to it at a very rapid 60 rate while the relatively cool oil prevents excessive heating of the metal walls of the tubes, even though subjected to the most highly heated portion of the combustion gases. The oil then traverses the lower row of the pipe section in the compartment 14, in which it is also heated rapidly, especially near the front of the furnace. As it 65 passes thru the next two rows of the radiant section, it is heated at a decreasing rate to an exit temperature of 875-900° F. It then enters the 70 final soaking section extending from D in pass 14 to B in pass 15, through which it flows concurrently with the combustion gases, so that the temperatures of the oil and the combustion gases heating it gradually converge and the rate of application of heat to the oil therefore gradually de-

creases. By operating in this manner, the conditions required by this invention, that the metal walls of the tubes (while clean) through which the oil flows be at no point more than 20° F. above the maximum temperature to which the stream of oil is heated, may be maintained. This specification is made not because any greater overheating would injure the tubes, but as a measure of the rate of heat input. When coke does form, the temperature difference will go somewhat higher, but rate of heat input will remain about the same.

Operations in accordance with the present invention are preferably conducted upon oils which may be designated as clean cracking stocks; that is distillate oils the maximum boiling point of which in an Engler distillation at atmospheric pressure is not above 750° F. As set forth, above, the particular correlation of temperature and pressure is determined by the precise nature of the oil undergoing treatment. By operating upon such an oil in the manner above set forth, 12 to 20% gasoline or even higher may be produced from the oil in a single pass without refluxing and without extensive coke formation, the oil preferably being initially preheated to 20 say 400 to 500° F. by vapor heat exchange or by other suitable means. The other oils not regarded as clean cracking stocks may be operated on advantageously in accordance with the present invention, as the extent of conversion and/or length of run may be greatly increased by its use.

If desired, the products of conversion leaving the coil after being treated in accordance with the invention, may be retained at cracking temperature and pressure in an enlarged chamber for further conversion.

I claim:

1. The method of pipe still conversion of hydrocarbon oils under pressure which comprises flowing a distillate oil heavier than gasoline through a metallicly confined passage heated to cracking temperatures exceeding 850° F., retaining the oil within said heated passage until a conversion into gasoline boiling point fractions exceeding 12% of the oil introduced has been effected, maintaining a pressure such that the oil in said passage at its maximum temperature is in the state of a foam containing discontinuous vapor bubbles in a continuous fluid stream, and controlling the application of heat so that the maximum temperature attained by the metallic walls of the confined passage is not more than 20° F. higher than the maximum temperature attained by the oil.

2. The method of pipe still conversion of hydrocarbon oils under pressure which comprises flowing a distillate oil heavier than gasoline through a metallicly confined passage heated to cracking temperature, maintaining a velocity of flow of the oil through the passage of at least 60 lbs. per square inch of tube cross section per minute, maintaining a pressure upon the oil in the passage such that, at its maximum temperature, it provides a continuous flowing liquid stream in which vapor is present as discontinuous bubbles, and applying heat to the metallic walls of the passage at a maximum temperature not more than 20° F. above the maximum temperature of the oil.

3. The method of pipe still conversion of hydrocarbon oils under pressure which comprises flowing a distillate gas oil through a metallicly confined passage under pressure, the temperature attained by the oil and the minimum pres-

sure thereupon being so correlated that with a maximum temperature of about 915° F. the pressure is at least 1100 lbs. per square inch and with every 15° deviation from said temperature, a corresponding deviation of 100 lbs. in minimum pressure is permitted, retaining the oil within the heated passage until a conversion into gasoline boiling point fractions exceeding 12% of the oil introduced has been effected, and controlling the application of heat so that the maximum wall temperature attained by said passage is not over 20° F. above the maximum temperature attained by the oil.

4. The method of pipe still conversion of hydrocarbon oils under pressure which comprises flowing a distillate gas oil through a metallically confined passage under pressure, the temperature attained by the oil and the minimum pressure thereupon being so correlated that with a maximum temperature of about 915° F. the pressure is at least 1100 lbs. per square inch and with every 15° deviation from said temperature, a corresponding deviation of 100 lbs. in minimum pressure is permitted, maintaining a velocity of flow of the oil through the passage of at least 60 lbs. per minute per square inch of cross sectional area, retaining the oil within the heated passage until a conversion into gasoline boiling point fractions exceeding 12% of the oil introduced has been effected, and controlling the application of heat so that the maximum wall temperature attained by said passage is not over 20° F. above the maximum temperature attained by the oil.

5. The method of pipe still conversion of hydrocarbon oils under pressure wherein an oil heavier than gasoline is forced to flow through a confined passage in a furnace, applying heat to said confined passage to bring the oil to a temperature in excess of 850° F. in successive stages while maintaining the walls of the passageway at a temperature above the temperature of the contacting oil and not more than 20° F. above the maximum temperature attained by the oil, said confined passageway and flowing oil being heated by convection from hot combustion gases in an early stage of the flow, by radiant heat from the combustion chamber of the furnace in an intermediate stage of the flow, and in a later stage of the flow by convection from combustion gases cooled and previously used in heating the confined passageway in said early stage, and maintaining superatmospheric pressure upon the oil within the passageway.

6. The method of pipe still conversion of hydrocarbon oils under pressure in which an oil heavier than gasoline is caused to flow through a confined passage and heat is applied to said confined passage to bring the oil to a temperature in excess of 850° F. while maintaining the walls of the passageway at a temperature above the temperature of the contacting oil and not more than 20° F. above the maximum temperature attained by the oil while the oil is flowing in said confined passage through a furnace in successive stages, the confined passage with the flowing oil therein being heated by convection from hot combustion gases in said furnace in an early stage of its flow, and subsequently, in a later stage of its flow, by convection with said combustion gases traveling concurrently with the flow of oil through the passageway, after said gases have been used and

cooled in said early stage of flow, and maintaining a superatmospheric pressure upon the oil within the passageway.

7. The method of converting hydrocarbon oils which comprises introducing oil heavier than gasoline at a temperature below 750° F. into a continuous confined passageway, applying heat to said confined passageway to bring the oil passing therethrough to a temperature in excess of 850° F. while maintaining the walls of the confined passageway at a temperature above the temperature of the contacting oil and at no point more than 20° F. above the maximum temperature attained by the oil passing through the passageway and retaining the oil in the confined passageway until a conversion into lower boiling oils exceeding 12% of the oil introduced has been effected.

8. In the cracking of hydrocarbon oils, the method of heating which comprises passing a restricted stream of the oil at a high rate of velocity through a radiant heat zone of a furnace and heating the same therein to the desired maximum cracking temperature substantially entirely by radiant heat, thence passing the oil stream through a convection zone of the furnace, passing combustion gases from the radiant heat zone into the convection zone as a source of heat for the latter, and altering the heating characteristics of the combustion gases in transit from the radiant heat zone to the convection zone and prior to their use in the heating of oil in the convection zone to maintain the oil at said desired maximum temperature in the convection zone while avoiding any substantial increase in such maximum temperature.

9. In the cracking of hydrocarbon oils, the method of heating which comprises passing a restricted stream of the oil at a high rate of velocity through a radiant heat zone of a furnace substantially without the main stream of combustion gases and heating the same therein to the desired maximum cracking temperature preponderantly by radiant heat, thence passing the oil stream through a convection zone of the furnace, passing combustion gases from the radiant heat zone into the convection zone as a source of heat for the latter, and altering the heating characteristics of the combustion gases in transit from the radiant heat zone to the convection zone and prior to their use in the heating of oil in the convection zone to maintain the oil at cracking temperature to thereby effect soaking thereof.

10. In the cracking of hydrocarbon oils, the method of heating which comprises passing a restricted stream of the oil at a high rate of velocity through a radiant heat zone of a furnace substantially without the main stream of gases and heating the same therein to the desired maximum cracking temperature preponderantly by radiant heat, thence passing the oil stream through a convection zone of the furnace, passing combustion gases from the radiant heat zone into the convection zone as a source of heat for the latter, and altering the heating characteristics of the combustion gases in transit from the radiant heat zone to the convection zone by passing them in heat exchange relation with fluid conveying heat absorbing elements prior to their use in the heating of oil in the convection zone to maintain the oil at cracking temperature to thereby effect soaking thereof.

ROBERT E. WILSON.
